JOHN F. CHAMBERS, OF CALISTOGA, CALIFORNIA.

Letters Patent No. 75,859, dated March 24, 1868.

IMPROVED WASHING-MACHINE.

The Schedule referred to in these Letters Patent and making part of the same.

TO ALL WHOM IT MAY CONCERN:

Be it known that I, JOHN F. CHAMBERS, of Calistoga, county of Napa, State of California, have invented an Improved Washing-Machine; and I do hereby declare the following description and accompanying drawings are sufficient to enable any person skilled in the art or science to which it most nearly appertains to make and use my said invention or improvements without further invention or experiment.

The object of my invention is to provide an improved washing-machine, so constructed that, by means of wooden teeth, clothes, &c., may be rubbed upon a yielding corrugated metallic surface, in imitation of the rubbing upon a common wash-board by hand.

In order to accomplish this, I employ a square or oblong box, having a concave corrugated zinc bottom, with a centre-piece of wood or other material, made smooth. The beating or rubbing-apparatus consists of three or more boards, set edgewise in the box. The lower edges of the boards are slightly rounded, with a plane in the centre, and are provided with teeth, which are made in opposite directions to the plane, similar to saw-teeth. These beaters are suspended by an axle, which passes through upright standards, and has its bearings on the sides of the box, and are operated by an eccentric driving-shaft, having its bearings in standards.

To more fully explain my invention, reference is had to the accompanying drawings forming a part of this specification, of which—

Figure 1 is a side sectional elevation.

Figure 2 is a plan.

Similar letters of reference in each of the figures indicate like parts.

A represents the box or tub of my machine, which may be constructed of wood or metal. If made of wood it should have a metal-lined bottom, B. The bottom of the box is made concave by two pieces of corrugated metal or zinc, C C, similar to the corrugations of the common zinc washing-boards. These pieces are separated by a plane, D, which may be of wood, and attached to the bottom of the box. The pieces of zinc are unsupported from behind, except as the two ends are attached to the box, by which means elasticity or a yielding is had, which prevents the clothes from clogging. The beaters or rubbers E E E consist of boards set edgewise, with faces slightly rounded, and have teeth, F F F, cut on them, similar to saw-teeth, but in opposite directions to their centres, which are planes. These beaters are separated by standards, G G, to which they are attached. They are suspended by an axle, H, passing through the standards, which has its bearings upon the sides of the box, so arranged that the beater can be easily removed from the bearing. Above, the axle is attached by a pin and arm, having a band attached to it, which passes around an eccentric, I. A shaft, J, passes through this eccentric, having its bearings in standards attached to the sides of the box, with a driving-wheel, K, at one end, and a crank or pulley, L, at the other.

The operation of my machine, so far as I have described it, is as follows, to wit: Water, with soap or other compounds employed in washing, is placed in the box, and the clothes introduced at either end, but should not be placed under the beaters, as these only are intended to serve to turn the fabrics over, and press or rub them against the corrugated arc of the circle, having the same effect upon the pieces as if the hands were employed in washing with a common zinc-lined wash-board. The beaters are suspended in such a manner relative to the concavity that as the stroke is commenced from the plane or centre, the beaters are very near the corrugations, and as they ascend to the top, the space increases, the object being to lessen the power necessary to operate the machine, as well as to carry the clothes up to the top of the water in the machine at each end of the stroke.

To draw the pieces back as each stroke is made, I employ curved wires, M M, with continuous ends attached, which are bent downward so as to carry the clothes down with them, as the beaters move to and fro, as actuated by the eccentric in turning the driving-shaft. By this means the pieces are kept constantly turning, the beaters rubbing them at the upward stroke at each end of the machine, and allowing them to rise by disengagement near the centres of the corrugations.

A wringer, N, is attached to one end of the machine for wringing the fabrics for drying, previous to which, however, the beaters may be removed or elevated.

For heating the necessary water for boiling the clothes, I employ a furnace, O, which has a heating-surface of about the size of the bottom of the machine. This furnace has a fire-box, P, at one end, and a flue, P',

leading from it. An air-chamber, R, passes longitudinally through the furnace, and a removable cover, S, is placed at the rear end of the furnace.

The construction of the furnace may be varied to accommodate the size and shape of the machine, box, or tub.

After the clothes have been sufficiently washed they are passed through the wringer N, which is placed at one end of the machine, and the clothes hung out to dry, when the machine is removed from the furnace and the remaining fire or heat is used for heating the sad-irons, preparatory to ironing.

By this means great economy is had in washing and ironing fabrics, and the heat and steam in dwellings be avoided, as the whole may be used out of doors.

Having thus described my invention, what I claim, and desire to secure by Letters Patent, is—

The combination of the toothed beaters or rubbers E E with the yielding corrugated metallic bottom C C, constructed and operating substantially as described.

In witness whereof, I have hereunto set my hand and seal.

JOHN F. CHAMBERS. [L. S.]
